United States Patent Office

Des. 213,037

Patented Dec. 31, 1968

213,037

JAR OR SIMILAR ARTICLE

Floyd E. Pettengill, Lancaster, Ohio, assignor to Anchor Hocking Glass Corporation, Lancaster, Ohio, a corporation of Delaware

Original design application Sept. 23, 1966, Ser. No. 3,990.
Divided and this application Dec. 13, 1967, Ser. No.
9,754

Term of patent 14 years

(Cl. D9—92)

FIG. 1 is an elevational view of a jar or similar article showing my new design; and

FIG. 2 is a fragmentary sectional view taken along line 2—2 of FIG. 1.

The jar is generally circular in all cross-sectional views and the side opposite that seen in FIG. 1 is the same in appearance as the side shown.

The dominant features of my design reside in the portions shown in full lines.

The present application is a division of co-pending United States design patent application Ser. No. 3,990, filed Sept. 23, 1966.

I claim:

The ornamental design for a jar or similar article, substantially as shown and described.
